S. J. STEIN.
ATTACHMENT FOR PNEUMATIC TIRES.
APPLICATION FILED DEC. 21, 1918.

1,324,702.

Patented Dec. 9, 1919.

UNITED STATES PATENT OFFICE.

SAMUEL J. STEIN, OF GREENWOOD, MISSISSIPPI.

ATTACHMENT FOR PNEUMATIC TIRES.

1,324,702.

Specification of Letters Patent.

Patented Dec. 9, 1919.

Application filed December 21, 1918. Serial No. 267,814.

To all whom it may concern:

Be it known that I, SAMUEL J. STEIN, a citizen of the United States, and a resident of Greenwood, in the county of Leflore and 5 State of Mississippi, have invented a new and Improved Attachment for Pneumatic Tires, of which the following is a full, clear, and exact description.

My invention relates to a non-skid, puncture-proof protector adapted to be applied to a pneumatic tire, and the invention has 10 for an object to provide a protector composed of annular series of plates having non-skid elements and hinged together, certain 15 of the hinges being formed to present end members adapted for connection with the elements employed for fastening the protector to a wheel.

The above and other objects as will appear are attained by the novel construction and arrangement of parts hereinafter particularly described.

Reference is to be had to the accompanying drawings forming a part of this specification, it being understood that the drawings are merely illustrative of one example of the invention.

Figure 1 is a plan view of a portion of a device embodying my invention;

30 Fig. 2 is a longitudinal section on the line 2-2, Fig. 1;

Fig. 3 is an enlarged section on the line 3-3, Fig. 1;

Fig. 4 shows in side elevation a portion 35 of a wheel with a portion of my protector in place;

Fig. 5 is a detail showing in cross section a portion of the wheel rim with the means of securing the fastening elements to the 40 rim.

In carrying out my invention in practice, a series of plates 10 are provided adapted to lie on the outer surface of a tire A as in Fig. 4. To provide non-skid members 45 the several plates in practice are provided with punched up protuberances 11 and also, the side edges of the plates are provided with out-turned flanges 12 which in addition to contributing to the non-skid character of the protector serve to strengthen 50 the plates.

The plates are hingedly connected to one another. Alternate hinges may be of known form involving alining knuckles 13 and a 55 hinge pin 14 passing therethrough. Others of the hinges, preferably alternate ones, con-

sist of tubular edge portions 15 on adjacent transverse edges of the plates, the adjacent tubular members lying in close relation and parallel. Through tubular edges 15 of a pair extend double pins 16 which are given a form to adapt them to connect with fastening members adapted to be fastened to the wheel on which the protector is employed. Each pin 16 is formed of a continuous 65 length of rod or wire returned on itself, thereby presenting a loop 17 at one end of the double pin projecting beyond the side edges of the plates 10. At the opposite end the terminals of the double pin 16 are return bent in hooked form as at 18 disposed beyond the adjacent side edges of the plates. The ends of the double pin 16 presenting respectively a loop 17 and hooked terminals 70 18 are utilized for connecting with the protector the fastener elements which may consist, as indicated, of lengths of chain 19. At one side of the protector the ring 20 of a fastener element 19 passes through the loop 75 17 while at the opposite side the ring embraces the double pin 17 and is held against displacement by the return hooked ends 18. The elements 19 at the inner ends may be made fast to the wheel in any approved manner; as here shown each element 19 extends to the interior of the rim B of the 80 wheel and is secured by a thumb screw 21 in said rim and adapted to be given a quarter turn. With the head of the thumb screw parallel with the links, the inner end 85 link of the element 19 may be passed over said head after which the screw is given a quarter turn to dispose the head of the screw transverse to the chain link as indicated in dotted lines in Fig. 5. By providing pins 90 16 of a form to connect with the fastening elements, the use of separate means on the protector for connecting said elements is 95 avoided.

I would state in conclusion that while the 100 illustrated example constitutes a practical embodiment of my invention, I do not limit myself strictly to the mechanical details herein illustrated since manifestly the same can be considerably varied without departure from the spirit of the invention as defined in the appended claims.

Having thus described my invention, I claim as new, and desire to secure by Letters Patent:

1. A tire protector including a series of 110 protector elements, hinge means uniting said

elements, said hinge means at certain of the hinge connections comprising tubular edges on adjacent elements and parallel with each other, and double pins therein, said pins being united at one end by an integral loop, the terminals of said pins at the opposite ends thereof being returned in hooked form in opposite directions; together with fastener elements adapted to be secured to a wheel, and rings on said elements and connected with said pins, those rings at one side of the protector passing through the loops of the pins, and those rings at the

opposite side of the protector embracing said pins inward of the returned terminals 15 thereof.

2. A tire protector including a series of protector sections, and double hinge pins linking adjacent protector sections together, said pins presenting transversely disposed 20 parallel members hinged to the respective ends of the adjacent sections; together with fastener means to secure the protector on a wheel, the ends of said double pins having members secured to said fastener means.

SAMUEL J. STEIN.
